(57) **CLAIM**

The ornamental design for an air delivery adapter for respiratory mask with heat and moisture exchanger unit for respiratory mask, as shown and described.

DESCRIPTION

FIG. 1 is a front perspective view of an air delivery adapter with heat and moisture exchanger unit for respiratory mask showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front perspective view of an air delivery adapter with heat and moisture exchanger unit for respiratory mask showing a second embodiment of our new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken line is included for the purpose of illustrating portions of the air delivery adapter for respiratory mask with heat and moisture exchanger unit for respiratory mask device and forms no part of the claimed design.
